SHOETREE

Donald H. Mitchell, Chicago, Ill.

Application October 10, 1934, Serial No. 747,760

4 Claims. (Cl. 12—128.1)

My invention relates to shoe trees and has to do more particularly with shoe trees of the type adapted to be inserted in a shoe and yieldingly held there under pressure between the toe and heel so as to hold the shoe in shape.

One of the objects of my invention is to provide a shoe tree of the above character which is cheap to manufacture, simple of construction, light in weight, and easily applied and removed. For a better understanding of my invention, reference is to be had to the accompanying drawing in which:

Fig. 1 is a perspective view showing the preferred form of my invention.

Fig. 2 is a side elevation of the device of Fig. 1.

Fig. 3 is a top plan view of Fig. 2.

Fig. 4 is a modified form of toe construction.

Fig. 5 is another modified form of toe construction; and

Fig. 6 is a modified form of heel construction. Referring more in detail to the preferred form of my invention as shown in Figs. 1 to 3, the device is preferably made up of spring wire formed into a continuous member, the ends of which may be suitably connected in any manner, such as by welding, tie plates, or otherwise.

The toe portion of the tree extends forwardly as a loop 7, the extreme end of which is bent inwardly at 8 so as to prevent the wire loop from otherwise entering between the sole and upper of the shoe when they become separated. The forwardly extending or toe portion of the device is connected with the heel portion by an intermediate yielding loop 9 which extends downwardly into the back stop 10, which latter is formed up from tin or sheet metal and formed around the wire so as to provide a smooth rear portion. This plate 10 is also arranged in this particular form of the device to act to interconnect the ends of the wire at the rear loop. In other words, in this form of the shoe tree the ends of the spring wire are not welded or riveted together, but are inserted down into the plate 10 and held thereby.

Thus the device may be made up very cheaply, is light in weight, simple of construction, and still very effective in its use.

In Fig. 4 I have shown another form of toe construction, that is, instead of looping the toe end

back as in Fig. 1, I place a sheet metal cap over the end to prevent the wire from entering between the sole and the upper.

In Fig. 5 I show another modified form of toe in which I bend the tip upwardly and curve it 5 backwardly.

In Fig. 6 I have shown the ends of the wire welded at 11 instead of using the sheet metal plate 10 to hold the ends together.

I claim:

1. A shoe tree comprising a single strand continuous spring wire member having a forwardly extending loop with generally parallel sides for insertion in the toe of the shoe, the rear end being bent upwardly and then downwardly to form a 15 yielding back stop to rest against the back of the shoe.

2. A shoe tree comprising a single strand continuous spring wire member having a forwardly extending loop with generally parallel sides for 20 insertion in the toe of the shoe, the rear end being bent upwardly and then downwardly to form a yielding back stop to rest against the back of the shoe, the loop end of the toe portion being shaped to prevent the wire loop from entering 25 between the upper and sole of the shoe.

3. A shoe tree comprising a single strand continuous spring wire member having a forwardly extending loop with generally parallel sides for 30 insertion in the toe of the shoe, the rear end being bent upwardly and then downwardly to form a yielding back stop to rest against the back of the shoe, the loop end of the toe portion being shaped with its transverse center portion bent away from the position corresponding to the 35 tip of the sole to prevent the wire loop from entering between the upper and sole of the shoe.

4. A shoe tree comprising a single strand continuous spring wire member having a forwardly extending loop with generally parallel sides for 40 insertion in the toe of the shoe, the rear end being bent upwardly and then downwardly to form a yielding back stop to rest against the back of the shoe, the wire of the toe portion extending forwardly on both sides and then rearwardly 45 toward the center to prevent the wire loop from entering between the upper and sole of the shoe.

DONALD H. MITCHELL.
